(57) **CLAIM**

The ornamental design for a vehicle interior light, as shown and described.

DESCRIPTION

FIG. 1 is a front perspective view of the top of a vehicle interior light showing our new design;

FIG. 2 is a front perspective view of the bottom of the vehicle interior light of FIG. 1;

FIG. 3 is a top plan view of the vehicle interior light of FIG. 1;

FIG. 4 is a bottom plan view of the vehicle interior light of FIG. 1;

FIG. 5 is a right side elevational view of the vehicle interior light of FIG. 1;

FIG. 6 is a front elevational view of the vehicle interior light of FIG. 1;

FIG. 7 is a left side elevational view of the vehicle interior light of FIG. 1; and,

FIG. 8 is a rear elevational view of the vehicle interior light of FIG. 1.

The broken lines in the drawings form no part of the claimed design.
